(57) **CLAIM**

The ornamental design for a mold blank for a press, as shown and described.

DESCRIPTION

FIG. 1 is a top perspective view of a first embodiment of a mold blank for a press showing the new design.

FIG. 2 is a bottom perspective view of the mold blank for a press of FIG. 1.

FIG. 3 is a right side view of the mold blank for a press of FIG. 1.

FIG. 4 is a left side view of the mold blank for a press of FIG. 1.

FIG. 5 is a front view of the mold blank for a press of FIG. 1.

FIG. 6 is a back view of the mold blank for a press of FIG. 1.

FIG. 7 is a top view of the mold blank for a press of FIG. 1; and,

FIG. 8 is a bottom view of the mold blank for a press of FIG. 1.

The uniform dash-dash broken lines depict portions of the mold blank for a press that form no part of the claimed design. The dash-dot-dash lines and bracket are intended to show a symbolic break in the mold blank for a press. The appearance of any portion of the article between the break lines forms no part of the claimed design.
